Primary Examiner — Cynthia M. Chin

(57) **CLAIM**

The ornamental design for a toy building brick, as shown and described.

DESCRIPTION

FIG. 1 is a front top isometric view of a toy building brick showing my new design;

FIG. 2 is a bottom isometric rear view of the toy building brick;

FIG. 3 is a front side view of the toy building brick, a rear side view being a mirror thereof;

FIG. 4 is a top view of the toy building brick;

FIG. 5 is a bottom view of the toy building brick; and, FIG. 6 is a top isometric view of the toy building brick. The broken lines are for the purpose of illustrating portions of the article that form no part of the claim.
